UNITED STATES PATENT OFFICE.

JOSEPH L. HILLER, OF MATTAPoisETT, MASSACHUSETTS.

CENTRIFUGAL MACHINE.

1,367,046.

Specification of Letters Patent.

Patented Feb. 1, 1921.

Application filed February 26, 1919. Serial No. 279,332.

To all whom it may concern:

Be it known that I, JOSEPH L. HILLER, a citizen of the United States, residing at Mattapoisett, in the county of Plymouth and State of Massachusetts, have invented certain new and useful Improvements in Centrifugal Machines, of which the following is a specification.

The principal objects of the present invention are first, in the continuous operation of the machine, to permit the solid material to remain quiescent on the filtering or permeable member and to discharge the treated solid material without scarifying that member; second, to provide improved means whereby the centrifugal process of treatment can be successfully made continuous; and third, to provide reliable, durable and efficient mechanism for effecting discharge of the treated material while the machine is in operation.

The invention will be claimed at the end hereof but will be first described in connection with the embodiment of it chosen from among other forms of embodiment for the sake of illustration in the accompanying drawings forming part hereof and in which—

Figure 1, is a top or plan view with parts broken away and with other parts in section.

Fig. 2, is a sectional elevation partly in section on the line 2—2 of Fig. 1, and

Fig. 3, is a development of cam mechanism hereinafter described.

There is a circle of baskets or carriers 1, each oscillatable about an upright axis α , and each having ends 2 and 3, and a vertical concavo-convex wall 4, connecting the ends and disposed to one side of the axis of oscillation α . The vertical wall 4, is permeable and for that purpose its central portion 5, is shown as perforated and lined with a screen or filtering material 6. This vertical wall 4, is provided at one margin with a flange 7, for engagement with a margin 8, of the vertical wall of an adjoining carrier or basket so as to permit in effect a continuous wall. 9, is a rotating frame upon which the carriers 1, are mounted, as by pintles 10, for oscillation about their individual axes α . The frame 9, is shown as suspended from a fixed housing 11, by means of a ball and socket joint 12, and the frame 9, is shown as rotated by an electric motor 13. Upon this frame 9, is mounted a second

frame 16, provided with a feed-channel 14, having spouts 15, of which two are shown, although the number is not material and these spouts depend so as to discharge in the direction of the baskets or carriers 1. 60 Frame 16, rests upon the upper annular ring of frame 9, so as to slide on it, as shown at the right in Fig. 2. The frame 16, is shown as provided with gear teeth 17, which mesh with a pinion 18, carried by the housing 11, 65 and driven by a pulley 19, when it is desired to rotate the frame 16, at a different speed or in a different direction from the frame 9. In some cases it may be desirable not to rotate the frame 16. There are means, operable while the frame 9 is rotating, and adapted to intermittently turn each carrier 1, about its axis of oscillation α , in one direction to present the concave face of its vertical wall 4, to the axis of rotation of the 70 frame 9, for feed, and in the other direction away from said axis of rotation, for discharge. These means are shown to consist of a cam groove and follower mechanism of which the cam groove element is on the 75 frame 16, and the follower element or elements are carried by the frame 9, so that the mechanism is operated in response to difference in speed between the two frames. More accurately, use is made of a double 80 cam groove 20—21, 20 being deeper, formed in the under face of the frame 16, and of double or mate followers 22 and 23, projecting from the top end of each basket or carrier 1 and of which 22 projects higher 85 than 23. At certain places around the machine the casing 24 carried by the frame 16, is continuous and directs relatively fluid matter into suitable receptacles 25, as shown at the right hand side in Fig. 2; and in other 90 places the casing 24, is cut away to permit of the escape of relatively solid matter over a guide 26, as shown at the left hand side in Fig. 2.

For the sake of a description of the mode 100 of operation it will be assumed that both frames 9 and 16, are rotating with a difference in speed between them, for example, it may be assumed that frame 9, is rotating counter-clockwise and that frame 16, is rotating at a slower speed in the same direction or is rotating clockwise or is standing still. Those of the baskets or carriers 1, which are receiving material from the chute 15, and those of the baskets or carriers 1, 110

in which the material is being subjected to centrifugal treatment have the concave faces of their walls 4, presented toward the axis of rotation of the frame 9, and while they 5 have a circular motion of translation they are otherwise at rest. One way of accomplishing this will now be described. The baskets tend to turn the concave faces of their walls 4, away from the center of rotation of the frame 9, because of the distribution of their weight and the weight of their load eccentrically in respect to their axis x , and this tendency is restrained by the action of the trailing follower 22, upon 10 the outer wall of the cam groove 20.

Those of the baskets or carriers 1, which are discharging their treated contents are turned, in the present instance, clockwise about their axis x , for example, through 20°, more or less, so as to present their concave faces away from the axis of rotation of the frame 9. When this is done the cam grooves 20 and 21, cooperate with the followers 22 and 23, as shown in Fig. 3, 25 from which it is evident that the loops in the cam grooves acting on the mate followers insure positive movement of each basket or carrier 1, and in that figure the arrows connect the mate followers, *i. e.*, the followers of a single basket or carrier, and by their 30 positions indicate steps in the turning movements of one basket or carrier 1. Under the influence of centrifugal action and as a basket or carrier is turned in the manner described about its axis x , the contents roll off the permeable portion of the vertical wall 4, and escape without scarifying the filtering material 6.

I claim:

40 1. In a centrifugal machine the combination of carriers each oscillatable about an upright axis and each having a vertical concavo-convex wall the central portion of which is permeable and a marginal portion 45 of which is not permeable and onto which the contents roll before discharging to avoid scarifying the permeable portion, a rotating frame upon which the carriers are mounted for oscillation about their individual 50 axes, and means operable while the frame is in rotation and adapted to turn each carrier about its axis of oscillation to present the concave face of its wall toward the axis of rotation of the frame for feed and for 55 centrifugal action and away from said axis of rotation for discharge, substantially as described.

2. A centrifugal machine comprising the combination of two frames, means for imparting a speed differential of turning movement between the frames, one frame being provided with a cam, and permeable carriers turnably mounted on one of said frames and each provided with a cam follower, whereby the carriers are turned about

their individual axis to present one of their faces alternately toward and away from the axis of rotation of the frame which carries them.

3. A centrifugal machine comprising the combination of two frames, means for imparting a speed differential of turning movement between the frames, one frame being provided with a cam, and carriers oscillatably mounted on the other frame and having a vertical concavo-convex permeable wall arranged to one side of the axis of oscillation and having at their top ends a cam follower substantially as described. 70 75

4. In a centrifugal machine the combination of two frames, means for imparting a speed differential of turning movement between the frames, one frame being provided with a cam groove, a circle of oscillatable carriers mounted on the other frame and each having its weight eccentrically distributed in respect to its axis of oscillation to cause it to tend to turn into discharging position, and a follower for each carrier adapted to trail on the outer wall of the cam groove 80 85 and restrain said tendency, substantially as described.

5. In a centrifugal machine the combination of two frames, means for imparting a speed differential of turning movement between the frames, one frame being provided with two cam grooves, each having a loop, a circle of oscillatable carriers mounted on the other frame and each having two followers 90 95 adapted to work in said cam grooves to oscillate the carriers, substantially as described. 100

6. In a centrifugal machine the combination of a circle of carriers respectively adapted to keep their contents independent from the contents of the others and each oscillatable about an upright axis and each having a concavo-convex wall the central portion of which is permeable and a margin of which is not permeable, said walls provided marginally with means for preventing escape of material in feeding between adjoining carriers, a rotating frame upon which the carriers are mounted for oscillation, means operable while the frame is rotating 105 110 and adapted to intermittently turn each carrier in one direction to present the concave face to the axis of rotation of the frame for feed and for centrifugal action and in the other direction for discharge, and a feeder arranged to discharge radially toward the concave faces of the walls, substantially as described. 115 120

7. In a centrifugal machine the combination of a circle of carriers respectively adapted to keep their contents independent from the contents of the others and each oscillatable about an upright axis and each having a concavo-convex wall, said walls provided marginally with means for prevent- 125 130

ing escape of material in feeding between adjoining carriers, a rotating frame upon which the carriers are mounted for oscillation, means operable while the frame is 5 rotating and adapted to intermittently turn each carrier in one direction to present the concave face to the axis of rotation of the

frame for feed and for centrifugal action and in the other direction for discharge, and a feeder arranged to discharge radially toward the concave faces of the walls, substantially as described. 10

JOSEPH L. HILLER.
